UNITED STATES PATENT OFFICE.

ALBERT SHORT, OF CEDAR VALE, KANSAS.

BREECHING.

971,695.

Specification of Letters Patent.

Patented Oct. 4, 1910.

Application filed October 10, 1908. Serial No. 457,112.

To all whom it may concern:

Be it known that I, ALBERT SHORT, citizen of the United States, residing at Cedar Vale, in the county of Chautauqua and State of 5 Kansas, have invented certain new and useful Improvements in Breeching, of which the following is a specification.

The present invention comprehends certain new and useful improvements in harness and the invention has for its object an improved breeching construction in which the breeching is adjustably connected to one of the supporting stays through the medium of a buckle that is interposed between the 10 breeching strap and the usual layer strap and is provided at its lower end with a perpendicularly and outwardly disposed extension affording a continuous bearing surface which abuts the adjacent longitudinal edge 15 of the layer strap, whereby to maintain the buckle in position against accidental displacement.

A further object of the invention is a device of this character embodying a filling 25 block fitted within the frame to permit the layer strap to extend smoothly thereacross, the layer strap being sewed to the breeching strap through the interposed filling block, thus holding the latter firmly in place to 30 further brace the buckle against displacement.

With these and other objects in view that will more fully appear as the description proceeds, the invention consists in certain 35 constructions and arrangements of the parts that I shall hereinafter fully describe and then point out the novel features of in the appended claim.

For a full understanding of the invention 40 and the merits thereof and also to acquire a knowledge of the details of construction, reference is to be had to the following description and accompanying drawing, in which:

45 Figure 1 is a side elevation showing my improved harness applied; Fig. 2 is a section on the line 2—2 of Fig. 1; Fig. 3 is a detail perspective view of the intermediate buckle, shown in Fig. 2; Fig. 4 is a section 50 on the line 4—4 of Fig. 2; and, Figs. 5 and 6 are detail views of the terminal buckle.

Corresponding and like parts are referred to in the following description and indicated in all the views of the drawing by the same 55 reference characters.

A harness constructed in accordance with my invention embodies a conventional breeching strap 1 that is provided at its outer face with the usual relatively narrow layer strap 2, the layer strap extending entirely around the breeching strap and being stitched along its longitudinal edges thereto as indicated at 2^a.

Interposed between the straps 1 and 2 at a suitable distance from the adjacent end of the breeching, is a vertically disposed buckle frame which is substantially rectangular and is composed of side bars 12 and upper and lower cross bars, designated 13 and 13^a respectively. The upper portion of the 60 buckle frame projects above the upper longitudinal edge of the layer strap 2 and is provided above and in close proximity to said edge with an intermediate cross bar 14, on which a strap-engaging tongue 15 is pivotally mounted at one end, the free end of the tongue being arranged to abut the upper cross bar 13 and being designed for adjustable engagement with the rear supporting stay or branch 9 of the hip strap 10. Above 65 the intermediate cross bar the upper portion of the buckle frame is deflected laterally and outwardly at an incline, as indicated at 12^a, so as to permit the free end of said stay to extend downwardly across the layer strap 70 (see Fig. 2). A filling block 17 is fitted 75 within the buckle frame between the side bars 12 and the lower and intermediate bars 13^a and 14, and is of sufficient thickness to cause the layer strap to extend smoothly 80 across the frame, the layer strap being stitched to the breeching strap through the interposed filling block, so that the latter is effectually held in position and serves to 85 maintain the buckle frame against accidental displacement. The lower cross bar 13^a is extended outwardly substantially at 90 right angles to the plane of the buckle frame and affords a continuous upwardly facing bearing surface 19 that abuts against the 95 lower longitudinal edges of the layer strap and filling block to positively hold the buckle against accidental displacement when subjected to excessive upward strain. This extended portion projects outwardly beyond 100 the layer strap and is slotted beyond the same to constitute a keeper loop 16 for retaining the free end of the stay 9.

The intermediate buckle hereinbefore described and incorporated in the breeching in 110

the manner specified, forms the essential feature of the present invention. It will be apparent that such an arrangement embodies to a marked degree the characteristics of 5 simplicity and strength and is both inexpensive and thoroughly practical and efficient.

The breeching may be connected at its end to the forward stay 9^a in any approved 10 manner, although the preferred means for effecting this connection is illustrated in the drawing, wherein I have employed a terminal buckle, the frame of which consists of side bars 3 and upper and lower cross bars 15 4. In proximity to the upper cross bar the frame is provided with an intermediate cross bar 7 on which is pivotally mounted a tongue 8 designed for adjustable engagement with the forward breeching stay. 20 Above the cross bar the upper portion of the buckle frame is deflected laterally and outwardly at an incline (see Fig. 5), so as to permit the said stay to extend freely downwardly across the buckle frame and to be 25 readily inserted through a substantially perpendicularly and outwardly disposed keeper loop 11 carried by the lower cross bar 4. Between the intermediate and lower cross bars, the side bars of the frame are bowed oppositely, as indicated at 5, the layer strap passing 30 around one of said bowed portions to pivotally connect the terminal buckle to the breeching. A holdback strap 6 is passed about the other bowed portion and in the 35 present instance, in a double harness, connects the breeching to the choke strap to

permit the draft animal to hold back on the vehicle when going down hill.

In the foregoing description only one-half of the breeching, that is, the part of 40 the breeching on one side of the horse, has been referred to, but it is to be understood that the other half of the breeching is a duplicate of the part described.

Having thus described the invention what 45 is claimed as new is:

A harness including a breeching strap, a layer strap, a buckle frame interposed between the said straps, with its end portions projecting beyond the opposite longitudinal edges of the layer strap, a buckle tongue carried by one of the projecting end portions of the frame, a substantially perpendicularly outwardly disposed extension formed at the other projecting end portion of the 50 frame and providing a continuous outstanding bearing shoulder abutting against the adjacent longitudinal edge of the layer strap to hold the frame against displacement from the straps, the extension projecting outwardly beyond the outer face of the layer 55 strap and being formed beyond the same with a slot and a breeching stay engaged with the buckle tongue and extending across and lying against the outer face of the layer 60 strap with its free end retained in said slot.

In testimony whereof I affix my signature in presence of two witnesses.

ALBERT SHORT. [L.S.]
